METHOD AND MEANS FOR CONTROLLING TENSION AND TREMOLO EFFECTS

Filed March 3, 1926

UNITED STATES PATENT OFFICE.

BERTIE E. MILLS, OF OAK PARK, ILLINOIS, ASSIGNOR TO MILLS NOVELTY COMPANY, OF CHICAGO, ILLINOIS, A CORPORATION OF ILLINOIS.

METHOD AND MEANS FOR CONTROLLING TENSION AND TREMOLO EFFECTS.

Application filed March 3, 1926. Serial No. 92,002.

This invention relates particularly to an improved method and means for controlling the tension of strings in stringed instruments of the viol class in a music-playing machine.

5 The invention is peculiarly advantageous in providing a method and means for securing desired tension on the strings of such musical instrument while permitting the necessary freedom of action to produce a sensitively responsive tremolo effect, which being a salient object of the invention, the description hereinafter contained mainly relates thereto. The invention is not limited 10 to the use of a tremolo, however.

As is known, electrically operated violin machines are now on the market. The present invention is well adapted for use in connection with such machines, for example; 15 and in that connection reference may be had to United States Patent No. 1,441,702, dated January 9, 1923, and No. 1,068,935, dated July 29, 1913.

The invention is illustrated in its preferred embodiment in the accompanying drawing, which shows brokenly the neck-portion of a violin, the supporting means therefor, tensioning means, and means cooperating with the tensioning means for producing a tremolo effect.

In the illustration given, A represents a portion of the frame of a violin-playing machine; B, the neck-portion of a violin mounted on said frame; C, C', vibratory levers which serve as portions of the tensioning means of the violin strings 1; C², a tension spring shown to be connected with one of the levers; and D, D', pulsating devices connected with the levers and cooperating with the levers to produce the tremolo effect.

It will be understood that while only two tensioning devices and tremolo devices are shown, each string of the instrument is 45 provided with a separate tensioning device and tremolo device; also, while only one tension-spring is shown, it is to be understood that each tension device is provided with a tension-spring.

50 Description of the tension and the tremolo devices for one string will suffice. Thus, the lever C, for example, is pivoted on the frame at 2 and is equipped with a segmental guide 3, in which the string bears and through 55 which the string may slip freely. The lever

C is also equipped with an adjusting device 4 by means of which the string may be made taut in its connection with the lever.

The spring C² preferably is a long coil-spring which may be made of comparatively light wire. The lever C ordinarily is set in a horizontal position and held thereby by the spring C² which serves as a normal tensioning means.

60 The pulsating device D which serves to actuate the tensioning-lever C about the pivot 2 preferably comprises a cylinder 5 containing a piston 5^a which is equipped with a connecting rod 5^b. The connecting rod has its upper end pivotally joined at 65 to the extremity of the lever C.

65 The coil-spring C² preferably is disposed at an angle of preferably about 45° to the normal plane of the lever C. This spring is adjusted to give the desired normal tension when the lever C is in the horizontal position, it being understood that the string 1 is so connected with the lever as to be under the proper normal tension when the lever C is in the horizontal position. One 70 end of the spring C² is shown connected with the pivot 6 by means of a link 7. The other end is connected with suitable tension-adjusting means, shown as comprising a pivoted lever 8 and an adjusting screw 9. 75 These parts are mounted upon a suitable bracket 10 attached to the frame A.

80 The piston 5^a is actuated in the cylinder 5 by air pulsations admitted to the cylinder. These air pulsations may be of any 85 desired frequency and may serve to give any desired amplitude of movement to the piston. Ordinarily, the cylinder is supplied with air pulsations by means of a suitable air pump (not shown). The pulsations 90 and amplitude of movement for the levers of the several strings ordinarily are different. That is, the character of the movement is suited to the string. For example, a heavier string may require a greater 95 amplitude of movement to produce the desired tremolo effect than does a lighter string.

100 The pistons 5^a are not intended to serve primarily as weights in the present construction. In fact, they are made as light as possible, consistent with suitable dimensions and strength, the purpose being to reduce the inertia of the moving parts. The pistons do serve, in a measure, as weights, 105 110

but this is incidental, as it has been discovered that greatly improved effects can be obtained by employing springs as the principal tensioning means.

5 In arranging the springs, it is desirable to adopt an arrangement which will produce no substantial variation in the pull which the spring exerts upon the lever, regardless of the position of the lever. In the illustration given, the desired result is obtained by the relation of spring and lever illustrated. Thus, in the amplitude of movement of the lever C which is illustrated by the broken dotted lines, the pivotal point 6 10 may move upwardly from its normal position to the upper position designated 6^a and may move downwardly to the lower position designated 6^b. This vibration may be produced by means of the air pulsations 15 in the cylinder 5. If we assume the lever C to be at its lowermost shown position, the spring acts along a line between the point 6^b and the point 11, that is the point where the other end of the spring is attached to the adjusting lever 8, and it is evident that 20 the leverage is indicated by a line 12 drawn perpendicular to the line between the points 6 and 11 and extending to a parallel line which passes through the pivot point 2. In 25 like manner, when the lever C is in the middle (normal position) the effective arm is designated by a line 13 perpendicular to the axis of the spring in this position and extending from the point 6 to a line passing 30 through the pivot point 2 and parallel with the axis of the spring in this middle position. In like manner, the effective lever-arm is indicated by the line 14 when the lever C is in its uppermost position. It 35 will be understood that the effective lever-arm is the longest when the lever C is in the lowermost position, and is the shortest when the lever C is in the uppermost position, and has an intermediate length when the lever is in the neutral position. On 40 the other hand, the spring possesses the least tension when it is acting upon the longest effective arm, possesses the greatest tension when it is acting upon the smallest effective arm, and possesses an intermediate tension when it is acting upon the intermediate effective arm corresponding with the horizontal position of the lever C.

45 From the description given, it is evident that the lever-arm varies inversely with the tension of the spring, so that there is a compensating effect. This enables the effective action of the tensioning means which includes the coil-spring to remain practically constant during the vibration of the lever, which vibrations produce the tremolo effect. Such an arrangement enables the pulsating apparatus to vibrate the tensioning-lever in 50 a manner to secure the best tremolo effect, it being evident that a spring is free from

the objection which attaches to the use of weights on the tensioning-lever. Owing to the inertia of weights, when attached to the tensioning-levers and employed as a part of or in association with pulsating means, 70 it is difficult to obtain the desired response to the pulsations; hence, it is desirable to make the reciprocating parts as light as practicable and to employ a spring as the main tensioning means. Experience has 75 demonstrated that it is possible to maintain all desirable uniformity of tension and produce only those gradual variations which are necessary to attain the best tremolo effects. Thus, a new technical effect is 80 secured by employing a combination of the character illustrated in the drawing.

It is possible, of course, to vary the lever and spring arrangement, but it is highly desirable to employ such arrangement as 85 will give a compensating effect by variation of the effective lever-arm inversely with respect to the spring tension.

If desired, the tremolo effect may be dispensed with. That is, the pulsating-means 90 comprising the devices D, D' may be omitted. The tensioning-levers and springs will, nevertheless, serve as the normal tensioning-means for the strings. The initial adjustment of the strings may be made at 95 the point 4, after which the levers and springs will automatically maintain the proper tension, regardless of stretching of the strings, which, in practice, is sufficient to cause a considerable variation in the position of the levers.

The foregoing detailed description has been given for clearness of understanding only, and no unnecessary limitations should be understood therefrom, but the appended 105 claims should be construed as broadly as permissible, in view of the prior art.

What I regard as new, and desire to secure by Letters Patent, is:

1. String-tensioning means for stringed instruments, comprising a tensioning-lever connected with an end portion of each string, a spring serving as the normal principal tensioning means for said lever, and means 110 for producing vibrations of said lever.

115 2. String-tensioning means for stringed instruments, comprising a tensioning-lever connected with an end portion of each string, a spring serving as the normal principal tensioning means for said lever, means for adjusting said spring, and means for producing vibrations of said lever.

120 125 3. String-tensioning means for stringed instruments, comprising a tensioning-lever connected with an end-portion of a string and extending away from said string, and a coil-spring connected with said lever and serving as the normal principal tensioning means for the lever, said lever and spring being so related that the effective lever-arm 130

will vary inversely with the tension of said spring when the lever is vibrated.

4. String-tensioning means for stringed instruments, comprising a tensioning-lever connected with an end-portion of a string and extending away from said string, means for rapidly varying the position of said tensioning lever, and a coil-spring connected with said lever and serving as the normal 45 principal tensioning means for the lever, said lever and spring being so related that the effective lever-arm will vary inversely with the tension of said spring when the lever is vibrated.

15 5. In a tremolo device for stringed instruments, a tensioning-lever connected with an end-portion of a string and extending away from said string, a pulsating device connected with said lever, and a coil-spring 50 connected with said lever and serving as the normal principal tensioning means for the lever, said lever and spring being so related that the effective lever-arm will vary inversely with the tension of said spring 55 when the lever is vibrated.

6. In a tremolo device for stringed instruments, a tensioning-lever connected with an end-portion of a string, and disposed in a plane substantially parallel with the plane 60 of the string and extending away from the string, means for rapidly vibrating said lever, and a coil-spring connected with said lever and serving as the principal normal tensioning means for the lever, said spring 65 having its axis disposed at an angle to said lever.

35 7. In a tension device for stringed instruments of the viol class, a tensioning-lever connected with an end-portion of a string 70 of the instrument and projecting away from the string in a plane substantially parallel

with the plane of the string, a coil-spring connected with said lever near its remote end and normally tensioned to hold the lever substantially in the first-mentioned 75 plane, and an adjustable spring-tensioning device disposed below the fulcrum of said lever and connected with said spring.

8. In a tremolo device for stringed instruments, a tensioning-lever connected with a string of the instrument and having a pivot near the point of attachment of the string, said lever projecting past the neck of the instrument, means for imparting vibrations to said lever, and a coil-spring 55 serving as the principal normal tensioning means of the lever, said spring having one end connected with the lever at a point some distance in front of the neck of the instrument and having the other end connected 60 with a stationary member at a point below the neck of the instrument.

9. In a tension device for stringed instruments, a tensioning-lever connected at one end-portion with the end-portion of a string 65 and pivotally supported near said point of connection, said lever occupying substantially a horizontal position when the string is under normal tension, and a coil-spring connected at one end with said lever at a 70 distance from its pivot and connected at the other end with a stationary support disposed some distance below the pivot of the lever.

10. The method of producing a tremolo 75 effect in a stringed instrument equipped with a tensioning-lever, which comprises normally spring-tensioning said lever and then imparting rapid vibrations to said lever.
